MEANS FOR ADJUSTING THROTTLE VALVES

Shirley S. Weeks, Providence, R. I.

Application December 23, 1935, Serial No. 55,829

6 Claims. (Cl. 137—139)

This invention relates to improvements in means for adjusting throttle valves.

Throttle valves, or the like, when employed to control liquid or gaseous fuel fed to a burner, are usually actuated automatically in response to changes in the steam pressure where the burner is used to produce such pressure in a boiler. The fuel is customarily supplied at a substantially constant pressure, which of course is available at the supply side of the throttling valve. When this valve is open relatively wide, the differential of pressure between its supply and delivery sides is not so great as when the valve is more nearly closed. Accordingly, it is highly desirable that in the adjustment of the valve its travel when near its most closed or minimum opening position be comparatively less or slower than when it approaches its maximum opening position. It is also desirable to provide means which enable the minimum and maximum positions of the valve to be adjusted independently of each other, to provide for variation in the travel of the valve between these two positions and to provide for a separate adjustment of the valve with respect to its seat, regardless of the other adjustments. The provision of means for adjusting a throttle valve as aforesaid is the principal object of this invention.

The best mode in which I have contemplated applying the principles of my invention is shown in the accompanying drawing but these are to be taken as merely illustrative and it is intended that the patent shall cover by suitable expression in the appended claims whatever features of patentable novelty exist in the invention disclosed.

In the accompanying drawing:

Figure 1 is an elevation, partly in section on line 1—1 of Figure 3, of means embodying my invention;

Figure 2 is a side elevation, with a part broken away, showing a portion of the means for actuating the throttle valve;

Figure 3 is an end view taken from the right of Figure 2;

Figures 4, 5 and 6 are graphs, illustrating how the position of the valve may be varied by the novel adjusting means of my invention; and

Figure 7 is a view of a detail.

Referring more particularly to the drawing, the throttle valve is shown as having a cone head 1 on a stem 2 which is movable toward and from a seat 3 in the interior of a casing 4. This is, of course, merely indicative of any suitable form of control or throttle valve. An extended externally threaded cylinder 5 is secured to the casing by a

nut 6 and on this cylinder is mounted a frame 7 which is fixed in position by a lock nut 8. At the left or valve end of the cylinder a guide 9 is threaded therein for the valve stem and this guide also serves as a saddle for an expansion spring 10 coiled about the stem and pressing against a pin 11 extending therethrough. The right or frame end of the valve stem passes through a suitable packing or stuffing 12 which is held in place by the cap nut 13 having a central opening for access to the stem.

A cone seat 2a in the end of the valve stem is engaged by the conical point of an adjusting nut 14. The latter screws onto a split rod 15 having a bifurcated end 15a adapted to receive a lever 16 and be pivotally connected thereto by a pin 17. This lever has a series of holes 16' in its lower portion through which another pin 18 may be passed to pivotally connect the lever to arms 7a of the frame 7. These arms are also provided with a series of holes 7' so that by a proper selection of corresponding holes the fulcrum or pivot of the lever may be adjusted as desired.

The lever 16 rides on a small ball bearing 19 mounted on a pin 20 between two larger ball bearings 21, 22 also mounted on the same pin. The latter also carries the bifurcated end of a clevis 23 which screws onto a rod 24 that extends through a hollow guide 25 pivotally engaged at its upper end with a shaft 26. This shaft may be rotated by control apparatus (not shown) which, for example, may be responsive to the changes of steam pressure in a boiler. Secured to this shaft is a cam 27 which engages a roller 28 mounted in another clevis 29 on the rod 24. Between this latter clevis and the lower end of the guide 25 is a coiled spring 30 which tends constantly to keep the roller against the cam.

The larger ball bearings 21, 22 on the pin 20 ride on a plate 31 (see Figure 7) having slots 31a which enable the plate to be positioned on pin ends of two adjusting screws 32, 33 which are separately adjustable and may be locked in position by the nuts 34, 35 respectively.

The adjustments will now be described. Let it be assumed that the positions of the parts as shown in full line in Figure 1 represent the minimum valve opening. This opening may be adjusted by movement of the screw 32. Let the dotted positions of the ball bearings 19, 21, the lever 16 and the cone head 1 represent the maximum valve opening. This opening may be adjusted by movement of the screw 33. Referring to Figure 4 let the point *a* on the chart represent the minimum valve opening when the screw 32 is

positioned as shown in Figure 1 and let the point *b* on the chart represent the maximum valve opening when the screw 33 is in the position shown in Figure 1. If the latter is turned further inward, the maximum valve opening may be changed so that it may be represented by point *b* as seen in Figure 5, the point *a* remaining unchanged. Or if the maximum valve opening, as indicated by point *b* is as desired, the minimum valve opening may be changed to a greater amount by movement of screw 32 so as to be indicated by point *a* of Figure 6. Thus it is clear that either the minimum or maximum positions of the valve opening may be adjusted independently of the other by separate settings of the screws 32 and 33 respectively.

As the shaft 26 and cam 27 are rotated (by control means not shown) the roller bearings are moved along the plate 31. The lever 16 swings accordingly, as it remains in contact with the smaller bearing, and controls the intermediate positions of the valve between its minimum and maximum openings. To vary the movements of the valve between these positions, the fulcrum pin 18 may be shifted from one hole (16') to another in the lever 16, and to corresponding holes (1') in the arms 1a. The corresponding variations in the intermediate positions of the valve are indicated by the four curved lines *c* drawn on Figures 4, 5 and 6 between the points *a* (*a*!) and *b* (*b*!) representing the minimum and maximum valve openings. Thus by adjusting the pin 18, variations in the intermediate travel of the valve between its minimum and maximum positions may be attained.

If it is desired to change the valve position without changing either the position of screw 32 or screw 33 or the pin 18, then nut 14 may be turned on the pin 15. Suppose, for example, that the minimum opening is at point *a* on Figure 6, and the maximum at point *b* on the same figure. The intermediate travel is represented by the four lines *c*. If it is desired to reduce the valve opening in all of its positions, this may be accomplished by turning nut 14 clockwise (as seen from the right). The result is indicated on Figure 6 by the point *a*, the point *b* and the four lines *c*!

Thus the positions of the valve for either minimum or maximum openings may be independently adjusted without affecting the adjustment of the other, the travel of the valve between minimum and maximum positions may be independently adjusted without affecting these positions, and the valve opening for all positions may be independently adjusted without affecting the other adjustments.

The feature of my invention which provides for the slower opening of the valve when near its minimum position is accomplished by virtue of the lever 16 and its relation to the points of adjustment for the minimum and maximum valve openings. When the ball bearings are in or near the position shown in full lines in Figure 1, the point of engagement between the small bearing 19 and the lever 16 is relatively remote from the fulcrum pin 18. As the rollers move toward the adjusting screw 33, the point of engagement between the lever and the small bearing becomes closer and closer to the fulcrum pin. Thus it follows that the same movement of the rollers when near the minimum adjusting screw 32 will produce a slower or less opening movement of the valve than will be produced by the same movement of the rollers when the latter

are near the maximum adjusting screw 33. This variation in the travel of the valve is indicated by the lines *c* (and *c*!), it being evident that as the valve travels from the minimum opening *a* (or *a*!) toward the maximum opening *b* (or *b*!) it opens less rapidly near the minimum and more rapidly as it approaches the maximum. This feature has proven of great advantage in the adjustment of the valve to insure the proper proportioning of the fuel to the air supply for the burner.

I claim:

1. Means for adjusting a throttle valve or the like comprising, in combination, a valve stem; a lever whose movements control the movements of said stem; an adjustable plate; means interposed between the lever and plate and movable therealong to vary the position of said lever in accordance with the position of said plate; adjustable means for positioning one end of said plate to effect a minimum valve opening; and other adjustable means for positioning the other end of the plate to effect a maximum valve opening.

2. Means for adjusting a throttle valve or the like comprising, in combination, a valve stem; a lever whose movements control the movements of said stem; an adjustable plate; means interposed between the lever and plate and movable therealong to vary the position of said lever in accordance with the position of said plate; adjustable means for positioning one end of said plate to effect a minimum valve opening; other adjustable means for positioning the other end of the plate to effect a maximum valve opening; and means for changing the fulcrum of said lever to vary its movements between its positions corresponding to minimum and maximum valve openings.

3. Means for adjusting a throttle valve comprising, in combination, a support attached to said valve casing; a frame carried by said support; a valve stem extending through said support; a lever fulcrumed on said frame in position to engage said valve stem whereby the movements of the lever control the movements of the valve; separated adjusting means mounted on said frame; a plate carried at one end by one of said adjusting means and carried at its other end by the other of said adjusting means; means interposed between said plate and lever and movable therealong whereby the swing of said lever is determined by the position of said plate; the adjusting means at one end of the plate determining the minimum valve opening and the adjusting means at the other end of the plate determining the maximum valve opening.

4. Means for adjusting a throttle valve comprising, in combination, a support attached to said valve casing; a frame carried by said support; a valve stem extending through said support; a lever fulcrumed on said frame in position to engage said valve stem whereby the movements of the lever control the movements of the valve; separated adjusting means mounted on said frame; a plate carried at one end by one of said adjusting means and carried at its other end by the other of said adjusting means; means interposed between said plate and lever and movable therealong whereby the swing of said lever is determined by the position of said plate; the adjusting means at one end of the plate determining the minimum valve opening and the adjusting means at the other end of the plate deter-

mining the maximum valve opening; there being a series of holes in said lever and in said frame whereby the fulcrum of the lever may be altered to vary the swing of the lever and corresponding movement of the valve between its positions of minimum and maximum opening.

5. Means for adjusting a throttle valve or the like comprising, in combination, a valve stem; a lever whose movements control the movements 10 of said stem; an adjustable member; means interposed between the lever and said member and movable therealong to vary the position of said lever in accordance with the position of said member; adjustable means for positioning one 15 end of said member to effect a minimum valve opening; and other adjustable means for positioning the other end of said member to effect a maximum valve opening; the said lever being fulcrumed so that equal movements of said in- 20 terposed movable means will effect a lesser move-

ment of the valve when near its position of minimum opening than when near its position of maximum opening.

6. Means for adjusting a throttle valve or the like comprising, in combination, a valve stem; a lever fulcrumed near one end and having intermediate of its ends an operative connection with the valve stem whereby movements of the lever control the movements of said stem; means movable along said lever toward and from its 10 fulcrum; a member arranged to be engaged by said movable means throughout the movement thereof; adjustable means for positioning the end of said member remote from the lever's fulcrum to effect a minimum valve opening; and other adjustable means for positioning the end 15 of said member which is nearer said fulcrum to effect a maximum valve opening.
